FIG. 4. *INVENTOR*
D. J. Fox
by M. F. Brown & Son, May
ATTY'S.

UNITED STATES PATENT OFFICE.

DAVID J. FOX, OF BOSTON, MASSACHUSETTS.

AIR-MOISTENING DEVICE.

1,271,306.

Specification of Letters Patent. Patented July 2, 1918.

Application filed April 7, 1917. Serial No. 160,422.

To all whom it may concern:

Be it known that I, DAVID J. FOX, a citizen of the United States, residing at Boston, in the county of Suffolk and State of Massachusetts, have invented new and useful Improvements in Air-Moistening Devices, of which the following is a specification.

This invention relates to means for supplying water vapor to the intake manifold of an internal combustion engine, the water vapor mingling with the hydrocarbon fuel passing to the engine, and preventing or reducing to a minimum the deposit of carbon in the engine, said means including a water reservoir which may be located on the exhaust manifold and receive heat therefrom to vaporize the water, a vapor-conducting suction pipe connecting the vapor space in the reservoir with a portion of the engine such as the intake manifold, air and vapor being exhausted from the reservoir by the usual operation of the engine, and means for admitting an induced flow of air into said vapor space as required by the withdrawal of air and vapor therefrom.

The invention has for its chief object to enable the induced flow of air to forcibly contact with water in the reservoir and atomize the water, thus facilitating the formation of vapor.

To this and other related ends the invention consists in the improvements which I will now proceed to describe and claim.

35 Of the accompanying drawings forming a part of this specification,—

Figure 1 is a perspective view of a portion of an internal combustion engine embodying my improvements.

40 Fig. 2 is a sectional view on a larger scale than Fig. 1, showing the water reservoir, the exhaust manifold, and the intake manifold in transverse section.

Fig. 3 is a longitudinal section of the water reservoir on a larger scale than Fig. 2.

45 Fig. 4 is a plan view of the baffle plate hereinafter described.

The same reference characters indicate the same parts in all the figures.

50 In the drawings, 10 is a portion of an internal combustion engine provided with the cylinders 11, in each of which is the usual piston. As the piston operating mechanisms of the engine are of the usual construction, and form no part of the present invention,

it is believed unnecessary to show their construction in detail.

A carburetor 12 of any well known construction is provided, with the outlet therefrom communicating with the intake manifold 13 through which the hydrocarbon mixture is delivered to the cylinders 11. The engine is also provided with an exhaust manifold 14 through which the products of combustion escape from the cylinders 11.

15 represents a water reservoir which may be a cylindrical sheet metal tank, having in its upper portion a filling opening surrounded by a bushing 16, engaging a cap or closure 17 which is preferably hollow and forms the receiving end of an auxiliary air conduit through which a flow of air into the cylinder may be induced, as hereinafter described.

The upper portion of the reservoir has an opening surrounded by a fitting 18 forming the receiving end of a vapor conducting suction pipe, said fitting being internally tapered and having an internal screw-thread at its smaller end, engaging a threaded coupling 19 with which is connected one end of an elongated suction pipe 20. The opposite end of said suction pipe is connected at 21 with the intake manifold 13, said connection forming the delivering end of the suction pipe.

The reservoir 15 may be connected with the exhaust manifold by means including upper straps 22, saddles 23, to which the ends of said straps are attached, said saddles having ears 24, and lower straps 25, each riveted at one end to a saddle 23 and having a series of holes 26 in its opposite end portion, either of which is adapted to receive a screw 27 engaging the ear 24.

The upper straps and the saddles embrace the reservoir, and the saddles and lower straps embrace the exhaust manifold, said lower straps being rendered adjustable by the holes 26, screw 27 and ear 24.

At every down stroke of either of the pistons in the cylinders 11, a partial vacuum is created in the manifold 13, so that vapor-laden air is drawn from the vapor space in the reservoir and mixed with the hydrocarbon fuel passing to the cylinders. A flow of air into the cylinder is thereby induced, and the air is caused, in accordance with my invention, to forcibly contact with and atomize water above the water space in the

reservoir, in such manner as to provide an ample supply of vapor.

Referring to Fig. 3, 30 represents an elbow-shaped water-atomizing air conduit, the 5 substantially vertical receiving end of which is at the top of the reservoir and communicates with the atmosphere, while its substantially horizontal delivering end is below said top and arranged above a 10 body of water in the reservoir, said delivering end being preferably directed toward the receiving end of the vapor conducting suction pipe. 31 represents a water conduit in fixed relation to the atomizing 15 air conduit 30, and arranged to guide water upwardly from the body in the reservoir into the path of atomizing air delivered by the air conduit 30.

The action of the suction pipe causes air 20 to rush through the atomizing conduit 30, and at the same time raise water in the conduit 31. The conduits 30 and 31 constitute an atomizer, the air delivered by the conduit 30 impinging on the water delivered by 25 the conduit 31, so that a jet of air and atomized water is discharged into the space above the water in the reservoir, an ample supply of vapor being thus provided.

I prefer to interpose between said atomizer and the receiving end of the suction pipe means for intercepting water in the liquid state and permitting the passage of air and vapor. As here shown, I have embodied said means in a deflector 33, having 30 an orifice 34 to permit water in the liquid state to pass downward, and a baffle plate 35 provided with slots 36 (Fig. 4) and interposed between the deflector 33 and the end portion 18, said plate intercepting water 35 in the liquid state and permitting the passage of vapor.

37 represents a tube constituting an auxiliary air conduit connected with the cap 17 and extending downwardly therefrom 45 nearly to the bottom of the reservoir. When air-laden vapor is withdrawn from the reservoir by the suction pipe, air rushes through the auxiliary air conduit, and is delivered below the surface of the body of 50 water, so that the air passes through the water and takes up vapor in rising therethrough to the vapor space, an additional supply of vapor being thus provided.

The aggregate capacity of the air conduits 55 30 and 37 is greater than the conducting capacity of the suction pipe, so that the en-

tire volume of air admitted is greater than the volume of vapor-laden air withdrawn through the suction pipe. Air is therefore maintained at atmospheric pressure in the 60 reservoir, with the following useful results: first, the liability of collapse of the reservoir walls by pressure of the atmosphere thereon is prevented, and second, the vapor is diffused uniformly through the air space of 65 the reservoir and drawn from all parts thereof by the suction pipe. By thus dividing the air supply, I am enabled to so reduce the cross-sectional area of the atomizing conduit 30, that the atomizing jet of air 70 has greater atomizing efficiency than would be possible if enough air were admitted through the conduit 30 to maintain the air in the reservoir at atmospheric pressure. The conducting capacity of the suction pipe 75 may be determined by a removable disk 40 having an aperture 41, different disks with different sized apertures being used interchangeably. The air conduit 30 may be provided with an outwardly closing spring-pressed check valve 42, adapted to open inwardly.

I claim:

An air moistener for an internal combustion engine, comprising a water reservoir, 85 a suction pipe having its receiving end connected with the upper portion of the reservoir, and its delivering end connectible with the engine, an atomizing air conduit extending through the upper wall of the reservoir and open to the atmosphere, said conduit, having a delivering portion located above the water space in the reservoir, a water conduit associated with the atomizing conduit and having its receiving end in 90 said water space, and its delivering end above said space and in the path of air delivered by the atomizing conduit, and an auxiliary air conduit extending through the upper wall of the reservoir and open to the 100 atmosphere, the aggregate conducting capacity of the atomizing and auxiliary conduits being greater than the conducting capacity of the suction pipe, so that sufficient air is admitted to insure the presence of air 105 at atmospheric pressure in the reservoir, and a reduction of the cross-sectional area of the atomizing conduit, to cause an efficient atomizing action, is permitted.

In testimony whereof I have affixed my 110 signature.

DAVID J. FOX.
